Norman W. Dahm and Albert F. Keller,
San Diego, Calif.

Application September 29, 1947, Serial No. 141,638

Term of patent 14 years

(Cl. D31—4)

To all whom it may concern:

Be it known that we, Norman W. Dahm and Albert F. Keller, are citizens of the United States of America, residing at San Diego, in the county of San Diego and State of California, and have invented a new, original, and ornamental Design for a Fish Lure, of which the following is a specification, reference being had to the accompanying drawing, forming a part thereof.

Figure 1 is a top plan view of a fish lure, showing our new design. Figure 2 is a side elevational view of a fish lure, showing our new design. Figure 3 is a front elevational view of a fish lure, showing our new design.

We claim:

The ornamental design for a fish lure, substantially as shown.

NORMAN W. DAHM.
ALBERT F. KELLER.
